[57] CLAIM

The ornamental design for a cup holder assembly, as shown and described.

DESCRIPTION

FIG. 1 is a top, front, left side perspective view of a cup holder assembly showing our new design;
FIG. 2 is a top plan view thereof;
FIG. 3 is a rear elevational view thereof;
FIG. 4 is a side elevational view thereof, the opposite side being a mirror image;
FIG. 5 is a bottom plan view thereof; and,
FIG. 6 is a front elevational view thereof.

Fig. 2.

FIG. 4.

FIG. 5.

FIG. 6.
